UNITED STATES PATENT OFFICE

WALTER C. PARMLEY, OF UPPER MONTCLAIR, NEW JERSEY

PEN

Application filed November 23, 1925. Serial No. 70,778.

The present invention relates to pens which may be employed either with an ordinary pen holder or with a holder of the fountain pen type.

There is considerable variation in the kind of pen preferred by different individuals. Some people, in writing, bear down heavily on the pen, while others bear lightly on the pen, and a pen which would suit one person is often either too stiff or not stiff enough to suit another. Furthermore, a pen which is satisfactory to the user when writing upon one kind of paper may not write properly when used upon a different kind of paper.

The present invention has for its object to provide a pen in which the flexibility of the writing point may be varied to suit the requirements of the user.

A further object is to provide a pen capable of retaining a greater quantity of ink and requiring less frequent dipping than the ordinary pen.

With the above and other objects in view the invention may be said to comprise the pen as illustrated in the accompanying drawings hereinafter described and particularly set forth in the appended claims together with such modifications and variations thereof as will be apparent to one skilled in the art to which the invention appertains.

Reference should be had to the accompanying drawings forming a part of the specification in which Fig. 1 is a top plan view of a pen embodying the invention; Fig. 2 is a section taken on the line indicated at 2-2 in Fig. 1; Figs. 3 and 4 are a bottom plan view and a top plan view respectively, of a modified form of the invention; Figs. 5, 6 and 7 are sections taken on lines indicated at 5-5, 6-6 and 7-7 respectively, in Fig. 4; Fig. 8 is a top plan view illustrating another form which the invention may assume.

Referring first to Figs. 1 and 2 of the drawing, there is shown a pen having a concave body portion 1 which tapers toward its rear end and a point 2 of the usual form which may be split centrally to provide the usual writing nibs 3. A clasp 4 fits over the body portion 1 of the pen and has its opposite edge portions bent inwardly at 5 over the edge por-

tions of the concave body 1 to secure the clasp to the body portion of the pen. The clasp 4 may be slid longitudinally along the body portion 1 and, as it is moved toward the point 2, the clasp 4 will be gradually brought into tighter gripping engagement with the body to exert an inward pressure upon the opposite edges of the pen increasing the curvature thereof so that there will be a greater resistance to flexing movements of the point and body and the pen will be made stiffer. To increase the stiffness of the pen the clasp 4 is adjusted toward the point of the pen, and to make the pen more flexible the clasp 4 is adjusted away from the point of the pen. In order to prevent the clasp 4 from becoming detached from the pen a rivet 6 may extend through an opening in the clasp 4 and through a longitudinal slot 7 in the body portion of the pen. The longitudinal slot 7 will permit the longitudinal movement of the clasp 4 necessary to adjust the pen to the desired degree of flexibility.

In Figs. 3 to 7 of the drawing a modified form of the invention is illustrated by which a greater variation in the flexibility of the pen may be obtained and by which the ink retaining capacity of the pen is increased. In this modification the body portion 11 of the pen is tapered towards its rear end and the point 12 may be divided and provided with the usual writing nibs 13. A flexible reinforcing member 14 is secured upon the top of the pen and this reinforcing member has a shape which corresponds substantially to that of the pen. The reinforcing member 14 has a rearwardly tapering concave body 15 which is somewhat narrower than the body portion 11 of the pen and which may have a greater transverse curvature, so that the opposite edges of the reinforcing member 14 rest upon the top of the body portion 11 of the pen while the central portion of the reinforcing member is spaced from the body portion 11. The reinforcing member 14 also has a pointed end 16 which overlies the point 12 of the pen and is normally spaced a slight distance above the point 12. The point 16 of the reinforcing member terminates short of the writing point of the pen so that the

point of the pen only is used in writing. The rear end of the reinforcing member is secured to the rear end of the pen by means of integral tongues 17 which extend from the edges of the body portion 11 at the rear end thereof and are bent inwardly over the opposite edges of the reinforcing member 14. When the point of the pen is pressed against the paper, it will be bent upwardly toward the point of the reinforcing member 14, and as the said point approaches the reinforcing member the resistance to further bending movement will be greatly increased. The reinforcing member 14 also provides a reservoir 15 for ink between the under side thereof and the upper surface of the pen, and this ink will be gradually fed to the nibs of the pen during the writing operation.

Means is also provided for varying the flexibility of the pen and to this end a clasp 18 similar to the clasp 4 above described, is provided which embraces both the body portion 11 of the pen and the body portion 15 of the reinforcing member. By adjusting the clasp 18 toward the point of the pen, the opposite edges of the body portion 11 are crowded inwardly increasing the stiffness of the point 12, and at the same time the reinforcing member 14 is crowded toward the main pen reducing the space between the pen and reinforcing member and further increasing the stiffness of the pen.

In either of the modifications described, the clasp embracing the body portion of the pen 35 may be easily and quickly adjusted to a position such that the desired degree of flexibility is obtained by pressing the same along the pen either with a finger nail or with the blade of a pen-knife.

40 The form of the invention illustrated by Fig. 8 is very similar to that of Fig. 4 except that the pin and slot connection of Fig. 1 is utilized, the pin being designated by numeral 19 and the slot by numeral 20.

45 Having described my invention, what I claim is:

1. The combination with a pen having a point and a tapering concave body, of a clasp having a sliding fit with the sides of the body and adjustable thereon to exert a varying pressure on the body to vary the stiffness of the point.

50 2. The combination with a pen having a point and a tapering concave body, of a clasp having a sliding fit with the sides of the body and adjustable thereon to exert a varying pressure on the body to vary the stiffness of the point, said clasp having a pin and slot 55 connection with said pen.

60 3. The combination with a pen having at one end a point and a concave body tapering toward the end opposite the pointed end, of a clasp embracing the sides of said tapered body and adjustable thereon toward and

from the pointed end to increase or decrease the stiffness of the writing point.

4. A pen having a body portion and point, a resilient reinforcing member secured upon the top of the pen body, said reinforcing member being secured at its rear end to the pen and terminating adjacent the point of the pen, and a clasp embracing the pen and reinforcing member and adjustable thereon to hold the reinforcing member to the pen with varying pressure. 75

5. The combination with a pen having a tapering concave body and a point at one end, of a resilient reinforcing member of a shape similar to that of the pen, said reinforcing member being shorter and narrower than the pen and being secured at its rear end to the rear end of the pen, and a clasp slidably embracing the body of the pen and the reinforcing member and adjustable along the body of the pen to hold the reinforcing member against the pen with varying pressure and to vary the stiffness of the pen. 85

6. A pen having a tapering concave body and a point at one end, a resilient reinforcing member of a shape similar to that of the pen but shorter and narrower than the pen, said reinforcing member being secured upon the top of the pen and having a transverse curvature greater than that of the pen body, 90 said resilient member having a point terminating short of the point of the pen and a clasp embracing the pen body and reinforcing member and adjustable along said pen body to hold the reinforcing member against the pen with varying pressure. 95

In testimony whereof, I hereunto affix my signature.

WALTER C. PARMLEY.
